UNITED STATES PATENT OFFICE

ANDREW J. GALLAHER, OF ST. LOUIS, MISSOURI

MEANS FOR CLOSING OIL WELLS

Application filed May 26, 1930. Serial No. 455,490.

This invention relates to means for closing oil wells by utilizing the pressure within the wells to actuate a member controlling a closing device.

5 An object of the invention is to provide a plug designed and adapted to be located at the open end of an oil well, in combination with means actuated by the pressure escaping from the well to rotate the plug, and means 10 in association with the plug for moving the plug longitudinally to proper position to close the well.

Another object of the invention is to provide a rotary plug for closing an oil well, 15 in combination with means for connecting the plug to the well and a support through which the plug is screwed and whereby rotation of the plug will cause the plug to move to position to close the well, and means for 20 utilizing the pressure in the well for rotating the plug and causing the plug to become located in closing position.

Other objects will be made plainly apparent from the following description, reference being made to the accompanying drawings, in which—

Fig. 1 is a side elevation showing the device in connection with the casing of an oil well preparatory for operation to position to 30 close the well.

Fig. 2 is a side elevation after the plug has been moved to closed position.

Fig. 3 is an inner end elevation of the closing device.

35 Fig. 4 is an upper end elevation of the closing device.

Fig. 5 is a longitudinal sectional view of the device showing the propeller blades which rotate the device to closing position.

40 The plug which is used as the closing member to close the oil well casing 1 comprises a cylindrical body portion 2 having on one end a conical extension 3 and on the opposite end a cylindrical extension 4 of reduced diameter. This plug is designed and adapted to be moved to position within the oil well casing 1 to close the same and to be moved from the oil well casing in order to open the casing. The end of the conical extension 1 45 is formed with a number of twisted blades

5 having a radial length less than the radius of the body 2, so that said blades may move freely into and out of the casing 1.

A passage 6 extends from the apex of the cone 3 throughout the length of said cone and also through the body 2. This passage 6 also extends throughout the length of the stem 4.

55 A propeller attachment, comprising a body 7 and a reduced axial extension 8 of said body, is secured to the outer end of the stem 4. The axial extension 8 is externally threaded and is screwed into an internally threaded hole in the outer end of said stem 4. A passage 9 through the extension 8 is in continuation of the passage 6 and is bifurcated, comprising branches 10 through the body 7. These branches 10 extend obliquely through the body 7 and open below a number of propeller blades 11. These propeller blades are twisted in the manner of propeller arms, as will be 60 readily understood by reference to the drawing, so that the pressure passing from the branches 10 and impinging against the inclined surfaces of said propeller blades will cause the device to rotate, with the effect and 65 result that said device is thereby moved to position to close and seal the oil well casing 1. These blades 11 are twisted in the same direction as the blades 5, so that there is a propeller at each end of the device, and these 70 propellers cooperate to move the device to closed position. That is, the pressure impinging against the inclined surfaces of the propellers 5 and 11 is utilized as an actuating 75 medium for rotating the device.

80 The stem 4 is externally threaded and is screwed through a ring 12. The ring 12 has a pair of diametrically opposite arms 13 to which are pivoted the upper ends of links 14. The lower ends of the links 14 are connected 85 by turn-buckles 15 with the upper ends of co-operating links 16. The lower ends of the links 16 are pivoted to the outer ends of arms 17 extending radially from opposite sides of a ring 18 mounted on the upper end of the 90 oil well casing 1. The arms 17 support pivots 19 on which are mounted ratchets 20. The free ends of the ratchets 20 will slide downwardly along the outer surface of the oil well casing 1, permitting the ring 18 to be moved 95 100

to any desired position downwardly along said oil well casing. By engaging and biting into or against the surface of the oil well casing 1, the ratchets 20 will resist and prevent outward movement of the ring 18. Thus, these ratchets 20 will resist the pressure within the oil well and will hold the closing device in position to close the outer end of the casing.

10 In use, the device is mounted approximately as shown in Fig. 1, the ring 18 being placed on and slipped downwardly along the extended end of the oil well casing, the cone 3 being placed within the end of said casing.

15 The pressure escaping from within the oil well casing engages the propeller blades 5, thereby tending to rotate the device in a direction to cause the threaded engagement of the stem 4 with the ring 12 to move the device to closing position. The pressure passing outwardly through the passages 6 and 10 impinges against the underside of the propellers 11, thus causing said propellers 11 to cooperate with the propellers 5 effectively to rotate the device and cause the device to move to closing position.

I am aware that other means for utilizing the pressure to rotate the closing device may be used, such, for instance, as familiar worm and gear arrangements. I contemplate such equivalent variations as may be within the scope of the appended claims. I do not restrict myself in any unessential particulars, but what I claim and desire to secure by Letters Patent is:—

1. A device of the character described comprising a body adapted to be moved into the open end of an oil well casing and having a longitudinal passage therethrough, means at 40 the outer end of said passage for utilizing the escaping pressure to rotate said body, and means for moving said body longitudinally into an oil well casing when said body is rotated by said pressure.

45 2. A device of the character described comprising a body adapted to be moved into an oil well casing to close said casing and having a longitudinal passage therethrough, means for holding said body in connection with an oil well casing, propeller devices in 50 connection with said body in position to be impinged by the pressure passing from said passage and thereby rotated, and means for moving said body to position in the oil well casing when said body is rotated.

60 3. A device of the character described comprising a threaded stem, a body in connection with one end of said stem for movement into an oil well casing, said stem and said body having therethrough a longitudinal passage, a support in which said stem is screwed for turning movement into an oil well casing, means for securing said support to an oil well casing, a propeller device in 65 connection with said body for impingement

by the pressure passing from said casing, and means cooperating with said propeller for utilizing the pressure passing from said passage to rotate said body and said stem.

4. A device of the character described comprising a member having a longitudinal passage therethrough, means for moving said member longitudinally when said member is rotated, a device for supporting said member in connection with an oil well casing, and propeller devices at the opposite end of said member for impingement by pressure passing from the oil well casing to rotate said device and cause said device to be moved longitudinally by said means.

5. A device of the character described comprising a longitudinally movable member, devices for supporting said member in connection with an oil well casing, propeller elements in connection with said member adapted to be impinged by the pressure passing from the oil well casing, and means for moving said member longitudinally when said member is rotated by the pressure impinging against said propeller elements.

6. A device of the character described comprising a member having a longitudinal passage therethrough, means for supporting said member in connection with an oil well casing, a propeller device in connection with the inner end of said member, another propeller device in connection with the outer end of said member, means for conducting pressure from the oil well casing through said device and causing said pressure to impinge against the underside of the propeller device at the outer end of said member effectively to rotate said member, and means for moving said member longitudinally into the oil well casing when said member is rotated.

7. A device of the character described comprising an element for attachment to an oil well casing, means for holding said element from movement toward the end of the oil well casing, a support pivotally connected with said element, a member mounted for rotary and longitudinal movements in said support and having a longitudinal passage therethrough, a body in connection with said member for insertion into the oil well casing, means operated by the pressure passing from the oil well casing through said passage for rotating said member, and means for moving said member longitudinally through said support when said member is rotated.

8. A device of the character described comprising a holding element adapted to be engaged with an oil well casing, a support pivotally connected with said holding element, a closing member for the oil well casing mounted for rotary and longitudinal movements in said support, means for rotating said closing member by the pressure passing from the oil well casing, and means for moving said member longitudinally into the oil

well casing when said member is rotated as aforesaid.

9. A device of the character described comprising a holding member, means in connection with said holding member for gripping an oil well casing and preventing movements of said member longitudinally along said casing in one direction, links pivotally connected with said holding member, a support pivotally connected with said links, a closing member for the oil well casing mounted by said support for rotary and longitudinal movements and having a longitudinal passage therethrough, propeller devices in connection with the outer end of said closing member for rotating said closing member and located in position to be impinged and operated by pressure passing from said passage, and means for moving said closing member longitudinally when said closing member is rotated by said propeller devices as aforesaid.

10. A device of the character described comprising a holding member, means in connection with said holding member for gripping an oil well casing and preventing movements of said member longitudinally along said casing in one direction, links pivotally connected with said holding member, a support pivotally connected with said links, a closing member for the oil well casing mounted by said support for rotary and longitudinal movements and having a longitudinal passage therethrough, propeller devices in connection with the outer end of said closing member for rotating said closing member and located in position to be impinged and operated by pressure passing from said passage, means for moving said closing member longitudinally when said closing member is rotated by said propeller devices as aforesaid, and means in connection with the opposite end of said closing member in position to be impinged by the pressure passing from the oil well casing to cooperate with said propeller devices in rotating said closing member.

ANDREW J. GALLAHER.
